UNITED STATES PATENT OFFICE

2,650,118

WIRE GRIP

Harold C. Ripley and James J. Saul, Chicago, Ill.,
assignors to Reliable Electric Company, Chi-
cago, Ill., a corporation of Illinois

Application October 13, 1949, Serial No. 121,158

1 Claim. (Cl. 287—75)

1

This invention relates to a wire grip of the tapered shell and jaw type.

Most wire grips of this type, such as are commonly used in wire splicers and dead end connectors, depend primarily upon substantial wire tension for maintaining the connection between the wire and the jaws. However, experience has shown that oftentimes grips of this character are carelessly applied, or tension in the wire varies widely from time to time, with the result that the wire occasionally becomes separated from the grip. Furthermore, such a grip is not suitable for wire not under tension.

Accordingly, the object of the invention is to provide a wire grip wherein the gripping force between the wire and the grip is substantially independent of tension on the wire. With such a grip, the lineman is not required to "sag in" the wire with the same degree of care as is necessary with prior devices.

While our improved grip is illustrated and described as forming part of a wire splicer, the invention is applicable to other wire gripping devices, such as dead end connectors and the like.

Other objects and advantages of the invention will be apparent as the description proceeds, reference being had to the accompanying drawing wherein one form of the invention is shown. It is to be understood that the description and drawing are illustrative only, and are not to be taken as limiting the invention except insofar as it is limited by the claim.

In the drawing:

Fig. 1 is a side view, partly in section, of a wire splicer embodying our improved wire grip;

Fig. 2 is a sectional view on line 2—2 of Fig. 1;

Fig. 3 is a sectional view on line 3—3 of Fig. 1, and Fig. 4 is a sectional view on line 4—4 of Fig. 1.

Referring now to the drawing, the illustrated wire splicer has two half portions that are substantially symmetrical. Accordingly, the left hand half only will be described in detail.

The wire grip portion at the left hand end of the splicer comprises a tubular shell 6 having a tapering end portion 7 and an adjacent portion 8 having a non-tapering exterior.

A plurality of wire gripping jaws 10 are disposed within tapering end portion 7, and the jaw exteriors have a taper for cooperation with the interior surface of portion 1. Referring to Fig. 1, the farther jaws 10 are moved to the left, the smaller is the diameter of the composite jaws. Thus wires of various sizes may be accommodated.

The interior ends of jaws 10 are interconnected

with each other in any suitable manner, such as by member 13, so as to permit the jaws to move radially. Member 13 also insures uniform circumferential jaw spacing and uniform longitudinal jaw movement.

The construction above described is shown more fully in U. S. Patent No. 2,138,913 to W. G. Fotsch.

Our specific improvement resides in the provision of mechanical means for forcing jaws 10 into tapering end portion 7 so that the jaws securely grip an inserted wire 15 regardless of initial or later tension on the wire. To this end we provide one or more longitudinal slots 16 in portion 8 of shell 6. In the grip illustrated, there are two oppositely disposed slots 16.

A bearing member is provided within the shell adjacent jaws 10. As here shown, the bearing member comprises a circular disk 18 and a transverse pin 19. Disk 18 bears against the ends of jaws 10, and pin 19 bears against the disk. Pin 19 has projections 20 that extend through slots 16 to the shell exterior. Projections 20 may be slit, as shown in Fig. 3, and the portions thereby separated may be bent outwardly so that the pin will remain in proper position in the slots.

The exterior of shell portion 8 is threaded substantially throughout its length as shown at 30 22. A screw means or nut 23 engages threads 22 and upon rotation is movable longitudinally of the shell.

As previously mentioned, the right hand end of the splicer is the substantial duplicate of the left hand end.

A resilient means such as compressed spiral spring 25 may extend longitudinally of the shell interior between the pins 19 of the left and right ends. This spring maintains the various parts 40 of the splicer in desired position when the splicer is not in use, and it also applies an initial wire gripping force when wire 15 is inserted in jaws 10.

In applying our improved grip to a wire, screw means 23 is moved to the right so as to be substantially clear of slots 16. When wire 15 is inserted in the grip, the jaws recede within tapering portion 7 a distance sufficient to expand the jaws to permit the wire to pass through the jaws and reach member 13. Spiral spring 25 thereupon acts to move jaws 10 in the opposite direction to produce an initial gripping action between the jaws and wire 15. Screw means 23 is then rotated so it is moved into engagement with projections 20 of pin 19. Further rotation of the screw means causes pin 19 to force jaws 10 farther

into tapering end portion 7, thereby increasing the gripping force between the jaws and wire 15 to a desired value.

The gripping force thus provided is sufficient to insure that the connection between the wire and the grip will not be broken regardless of whether or not the wire is under tension, or whether the tension varies from time to time.

From the above description it is thought that the construction and advantages of our invention will be readily apparent to those skilled in the art. Various changes and modifications may be made without departing from the spirit or losing the advantages of the invention.

Having thus described our invention, what we claim as new and desire to secure by Letters Patent is:

A wire grip comprising a tubular shell having a tapering end portion and an adjacent portion having a non-tapering exterior, individual wire 15 gripping jaws in said tapering end portion for cooperation therewith, said adjacent portion hav-

ing opposed longitudinal slots, a bearing member within said shell and having a face adapted to engage the inner ends of said jaws, a pin extending transversely through said shell inwardly of said bearing member, the ends of said pin extending through said opposed slots and being enlarged exterior of said shell, and screw means threaded on the exterior of said adjacent portion for cooperation with the ends of said pin.

HAROLD C. RIPLEY.
